JAMES L. LINDERMAN, OF ROCKFORD, ILLINOIS.

Letters Patent No. 87,947, dated March 16, 1869.

IMPROVEMENT IN SEED-SOWER.

The Schedule referred to in these Letters Patent and making part of the same.

To all whom it may concern:

Be it known that I, JAMES L. LINDERMAN, of Rockford, in the county of Winnebago, and State of Illinois, have invented a new and useful Improvement in Seed-Sowers; and I do hereby declare that the following is a full and exact description of the same, reference being had to the accompanying drawings, and to the letters of reference marked thereon.

This invention relates to certain improvements in seed-sowers; and consists in regulating the delivery of grain from the seed-wheel to the tubes of a seeding-machine; and also in an improved device for agitating, or stirring the same, to which end certain details of construction are employed, which will hereinafter more fully appear.

In the drawings—

Figure 1 is a plan view of my invention.

Figure 2, a side elevation of the same.

Figure 3, a longitudinal vertical section through line x-x, fig. 1.

To enable others skilled in the art to make and use my invention, I will proceed to describe fully its construction and operation.

A represents a section of the hopper, or seed-box, constructed in the usual manner, provided with the partitions a a, between which revolve the delivery-wheels.

a' represents the seed-channels between the partitions a a, which are composed of the vertical partition a² and the slot a³, in the bottom of the seed-box.

B represents a metal flap, or apron, attached to the longitudinal rod b, to the outer end of which is rigidly attached the lever b¹, extending across the end of the seed-box, and having the handle b² and projection b³, which is provided with a screw-thread.

C represents a curved and slotted guide-bar, with a curvature corresponding to the arc of a circle described

by the lever b¹, in which works the projection b³, being confined therein by the set-screw c.

C¹ represents the driving-shaft within the seed-box, upon which are located the delivery-wheels.

C² represents rods running transversely through the shaft C¹, outside of the partitions a a, which are provided with orifices in their lower edges. These rods are adjustable, and may project equally far on both sides of the shaft, or they may be so arranged that their whole length may be on one side. Their function is to force the grain through, and to keep the same from clogging in the partitions a a.

The operation of my invention is as follows:

The hopper being filled with grain, and motion being imparted to the shaft C¹ in any desired manner, the rods C² are operated, which force a greater or less quantity of grain through the orifices, according as they are adjusted.

When the delivery-wheel throws too much seed into the channels, the end of the lever b¹ is raised, which turns the apron B outward and upward, thereby covering the apertures to as great an extent as the operator desires. The lever is held in place by the set-screw c.

Having thus fully described my invention,

What I claim as new, and desire to secure by Letters Patent, is—

1. The metal flap B, in combination with rod b and lever b¹, as and for the purpose set forth.
2. In combination with the above, the guide-plate C, lever b¹, and set-screw c, when arranged as described for the purpose set forth.

This specification signed and witnessed, this 18th day of January, 1869.
